(57) **CLAIM**

The ornamental design for a fluid applicator as shown and described.

DESCRIPTION

FIG. 1 is a perspective view of our design for a fluid applicator.

FIG. 2 is another perspective view of our design.

FIG. 3 is a top view of our design.

FIG. 4 is a front plan view of our ornamental design. The back plan view being the same as the front plan view.

FIG. 5 is a side plan view of our design. The other side plan view being the same as this side view; and,

FIG. 6 is a bottom view of our design.

The use of broken lines indicates that the portion of the article depicted in broken lines forms no part of the design and is not to indicate the relative importance of parts of a design.
